SUPERREGENERATIVE RECEIVER

Thomas M. Ferrill, Jr., Hempstead, and Benjamin F. Spencer, Garden City, N. Y., assignors to The Sperry Corporation, a corporation of Delaware

Application February 12, 1945, Serial No. 577,368

17 Claims. (Cl. 250—20)

1

This invention relates to wave receivers, and more particularly to receivers of the superregenerative type especially adapted for the reception of ultra-high-frequency signal waves or microwaves.

In general, a superregenerative receiver is well adapted for use at ultra-high frequencies. It combines inherent simplicity with high sensitivity. Its selectivity is relatively low, thus minimizing the requirement for frequency stability in both the transmitter and the receiver. Furthermore, if the logarithmic mode of operation is employed, the oscillations always build up to an equilibrium value before quenching occurs, regardless of the strength of the input signal. A superregenerative receiver of this type, therefore, has an inherent limiting action, so that it tends to suppress noise pulses of large amplitude but of short duration, as for example those due to automotive ignition systems.

In the past, the construction of a superregenerative receiver for use at ultra-high frequencies has had, in common with receivers of other types for use at these frequencies, the problems due to the small physical size of the reactive elements comprising the resonant circuit. As the frequency of the signal wave becomes higher, the requirements for these components become increasingly stringent. At ultra-high frequencies, it is extremely difficult to provide circuit components which combine suitable electrical properties with a mechanical design capable of maintaining these properties in spite of variations in temperature and humidity, vibration, and other frequently unavoidable variations in the operating conditions.

Accordingly, it is an object of the present invention to provide an improved superregenerative receiver.

A further object is to provide a superregenerative receiver of extremely compact construction in which the resonant circuit and the electron tube are combined in a single unit.

It is another object of the invention to provide a superregenerative receiver employing a velocity-modulation tube of the reflex type.

It is still another object of the invention to provide a superregenerative receiver employing a velocity-modulation tube which has substantial output in accordance with the received signals.

An additional object of the invention is to provide a superregenerative receiver employing a velocity-modulation tube, in which the quenching is accomplished by varying a control voltage.

Yet another object of the invention is to pro-

2

vide a superregenerative receiver employing a velocity-modulation tube and being of the self-quenching type.

A further object of the invention is to provide improved apparatus and instrumentalities embodying novel features and principles adapted for use in realizing the above objects and also adapted for use in other fields.

In accordance with a preferred form of the present invention, an electron tube, preferably of the reflex velocity-modulation type having a cavity resonator, is used in combination with a rectifier element to provide an improved superregenerative receiver especially adapted for use at ultra-high frequencies or in the microwave region. The tube and its resonator are adjusted for oscillation at the frequency of the input signal wave, and quenching is accomplished by periodically interrupting the oscillation. In a preferred arrangement, the receiver operates in the logarithmic mode, but it may be arranged to operate in the linear mode if desired.

The invention also contemplates the provision of unitary means for introducing the input signal wave and for utilizing the output of the tube; and, in a modified form, there is contemplated an arrangement for utilizing a portion of the velocity-modulation tube to develop the quenching voltage.

The above and other objects and features of the invention will be better understood by reference to the following description taken in connection with the accompanying drawing, in which like components are designated by like reference numerals and in which:

Fig. 1 is a schematic diagram of a superregenerative receiver in accordance with the present invention and utilizing separate quenching;

Fig. 2 is a schematic diagram of a modification of the superregenerative receiver of Fig. 1, in which self-quenching is utilized; and

Fig. 3 shows a unitary input and output system especially adapted for use with the receiver of Fig. 1.

Referring to Fig. 1 of the drawing, there is shown a reflex velocity-modulation tube 10 having a heater 11, a cathode 12, a control electrode 13, a smoother or accelerating grid 14, a cavity resonator 15 including resonator grids 36, and a reflector electrode 16. Smoother grid 14 is supported by and connected to cavity resonator 15. Heater 11 is connected to terminals 17, to which may be connected a suitable source of heater or filament power, not shown. Cathode 12 is connected through resistor 20 to a tap 18 on direct-

current potential source 19. Control electrode 13 is connected, through resistor 20, to a tap 21 on source 19. Cavity resonator 15 is connected by lead 22 and resistor 20' to the positive terminal of source 19, and this terminal is preferably also connected to ground, as shown at 23. Resonator grids 36 form a part of cavity resonator 15. Reflector electrode 16 is connected through resistor 20''' to a tap 24 on source 19.

A quench-frequency oscillator 25 is provided, and its high-potential output terminal is coupled by means of capacitor 26 to control electrode 13 when switch 65 is closed as shown in Fig. 1. The other output terminal of oscillator 25 is grounded as shown. The output of oscillator 25 preferably, but not necessarily, is sinusoidal in waveform. Similar quench-frequency oscillators 25', 25'', and 25''' are also provided. Oscillator 25' is adapted to have one terminal connected to the cathode 12, through a capacitor 26', upon closing of a normally open switch 65'. The other output terminal of oscillator 25' is grounded. Oscillators 25'' and 25''' are adapted to be connected in like manner to cavity resonator 15 and reflector electrode 16, respectively, upon closing of their respective switches 65'' or 65'''.

Cavity resonator 15 is provided with a coupling loop 27, which is connected by means of a coaxial transmission line 28 to a dipole antenna 29. A second coupling loop 39 in cavity resonator 15 is connected, by means of a coaxial transmission line 31, to a rectifier element 32. One end of loop 39 is connected to the outer conductor of line 31, and the other end to its center conductor. The output terminal of rectifier element 32 is by-passed to ground by a capacitor 9 which is shunted by a resistor 33, and is coupled to one of a pair of output terminals 34 by means of capacitor 35. The other output terminal is grounded as shown.

In operation, heater 11 is energized, causing cathode 12 to emit electrons which are attracted in the direction of the relatively positive smoother grid 14. The flow of electrons toward cavity resonator 15 is controlled by the potential of control electrode 13, which controls the magnitude of the electron current. The electrons pass through smoother grid 14, and then through resonator grids 36, being subjected to velocity modulation due to the action of the electric field between grids 36, and approach reflector electrode 16. Due to the negative potential of the latter, they are reversed in flight and again enter cavity resonator 15 travelling toward the cathode, where they give up energy to assist in maintaining oscillation and provide output energy. Assuming for the moment that quench-frequency oscillator 25 is rendered inoperative, velocity-modulation tube 10 oscillates at a frequency which depends principally upon the dimensions of cavity resonator 15 and to a minor extent upon the potentials of cavity resonator 15 and of reflector electrode 16 with respect to that of cathode 12. By proper choice or adjustment of these variables, the frequency of oscillation may be made to correspond with that of a signal wave intercepted by antenna 29 and introduced into cavity resonator 15 by means of transmission line 28 and coupling loop 27.

If quench-frequency oscillator 25 is now made operative, the self-oscillation of tube 10 will be periodically interrupted at the quench frequency, since the output of oscillator 25 is applied to control electrode 13. The rate at which the oscillatory field of resonator 15 builds up before

quenching takes place is a function of the amplitude of the signal wave intercepted by antenna 29. Hence, by detecting the average strength of oscillation of tube 10, as evidenced by the oscillatory field developed in cavity resonator 15 and picked up by coupling loop 30, an output voltage which corresponds with the envelope of the signal wave may be developed between output terminals 34.

The superregenerative receiver shown in Fig. 2 of the drawing differs from that of Fig. 1 in two principal respects. The receiver of Fig. 2 is of the self-quenching type, and hence requires no separate quench-frequency oscillator. Secondly, the output is derived from the change in cathode current of the velocity-modulation tube rather than by rectification of the oscillations developed in the cavity resonator of the tube.

In the arrangement of Fig. 2, cathode 12 and control electrode 13, together with the assembly comprising smoother grid 14 and resonator 15, are connected in a Hartley type of oscillator circuit with inductor 37 and shunt capacitor 38. Cathode 12 is coupled by means of capacitor 39 to a tap 40 on inductor 37. The lower end terminal 41 of inductor 37 is connected through grid-leak resistor 42, which is shunted by capacitor 43, to control electrode 13. The upper end terminal 44 of inductor 37 is coupled, by capacitor 45, to cavity resonator 15 and hence to smoother grid 14. Cathode 12 is maintained at a suitable direct potential, as determined by tap 48 on source 19, through choke coil 46. Likewise, the direct potential at control electrode 13 is maintained through choke coil 47, which is connected between tap 21 on source 19 and tap 40 on inductor 37.

The primary winding 48 of a transformer 49 is connected in series in the circuit between cathode 12 and tap 48 on source 19. Secondary winding 50 of transformer 49 is connected between output terminals 51.

Dipole antenna 29 is connected, by means of transmission line 28 and coupling loop 27, to cavity resonator 15 of velocity-modulation tube 10. As in Fig. 1, reflector electrode 16 of tube 10 is connected to tap 24 on source 19. Cavity resonator 15 of tube 10 (and hence smoother grid 14) is connected, by means of lead 22, to the positive terminal of source 19 and at 23 to ground. Coupling loop 30 is not used in this arrangement.

In operation, cathode 12, control electrode 13 and the assembly of smoother grid 14 and cavity resonator 15 serve as the three elements of a triode which, in combination with the resonant circuit comprising inductor 37 and capacitor 38, oscillates at a quench frequency the value of which depends upon the adjustment of capacitor 38. When thus oscillating, it modulates the electron stream which flows from cathode 12 through resonator grids 36 toward reflector electrode 16, the amplitude of modulation being chosen to be sufficient to render tube 10 periodically non-oscillatory.

The velocity-modulation tube operates in the same manner as described above in connection with Fig. 1, to provide oscillations at the carrier frequency of the incoming signal wave within cavity resonator 15. These oscillations are periodically interrupted due to the quenching action of the above-described oscillator circuit on the electron stream.

The rate at which oscillations build up before they are quenched is a function of the amplitude of the incoming radio wave intercepted by dipole

antenna 29 and introduced into cavity resonator 15 by means of transmission line 28 and coupling loop 27. The average strength of the oscillations depends on the strength of the input signal wave introduced by loop 27. The beam current of the tube varies to some extent with the strength of oscillations in the cavity resonator. Hence, the cathode current of the tube 10 varies as a function of the input-signal modulation envelope, so that an output voltage corresponding to the signal modulation is developed between output terminals 51.

In the arrangement of Fig. 1, the quench voltage is applied between the control electrode and the cathode of the velocity-modulation tube. In the receiver of Fig. 2, the quench voltage is effectively applied primarily between the cathode and the control electrode, with a secondary application between the cavity resonator and the cathode. It will be understood that it is within the scope of the present invention to apply the quench voltage between other electrodes or combination of electrodes of the tube. For example, the quench-voltage source could be introduced in lead 22 by closing switch 65'; meanwhile, switch 65 is opened to disconnect the quench oscillator 25 from the control electrode 13 so that the quench voltage would be effectively applied between cavity resonator 15 and cathode 12. In another modification, when switch 65''' is closed and switch 65 is opened, the quench voltage might be applied to reflector electrode 16 in such a manner as to vary the voltage of this electrode with respect to cathode 12 at the quench frequency. Still another arrangement would introduce the quench voltage at cathode 12 so that the potential of this electrode, with respect to all of the other electrodes of the tube, would change at the quench frequency; this is done by closing switch 65' and opening switch 65.

In Fig. 1 of the drawing, the output of the velocity-modulation tube is shown as derived by rectifying the oscillations developed in cavity resonator 15. In the arrangement of Fig. 2, the output of the receiver is developed by utilizing changes in the cathode current of the tube. It will be understood that these two different methods for obtaining the output of the tube may be interchanged between the systems of Figs. 1 and 2. In addition to the two methods shown in Figs. 1 and 2 and described above, the output of the velocity-modulation tube could also be obtained by demodulation of the quench voltage, since it has been found that the amplitude of this voltage, when the quench oscillator has relatively poor regulation, is a function of the average strength of oscillation existing in the velocity-modulation tube. It will be understood that the use of the latter method for obtaining the output of the receiver in either of the arrangements of Figs. 1 and 2 is within the scope of the present invention.

Fig. 3 of the drawing shows an assembly which replaces rectifier element 32 of Fig. 1, and makes it possible to introduce the incoming signal waves into cavity resonator 15 by means of the same coupling loop that is used to provide an output signal. In Fig. 3, transmission line 31 feeds into a crystal resonant chamber 52 which is tuned, by means of adjusting screw 53, to the carrier frequency of the incoming signal wave. Dipole antenna 29 is also coupled, through transmission line 28, to resonant chamber 52, instead of directly to cavity resonator 15 as shown in Fig. 1.

Resonant chamber 52 is shown diagrammati-

cally to illustrate how the transmission lines 28 and 31 are coupled to it, and how a miniature crystal detector 54 is arranged within it. Chamber 52 comprises a hollow cylindrical housing or body 55 of conductive material and having openings in its walls to receive lines 28 and 31. A cylindrical conductive rod 56 is positioned coaxially within housing 55, and is supported and insulated from the bottom of the housing by a dielectric disc 57. With respect to the high-frequency electromagnetic field within resonant chamber 52, rod 56 serves as a reentrant portion of a cavity resonator formed by the combination of the rod and housing 55. Discs 58 and 59, arranged in spaced relation with respect to rod 56, are attached to the inner conductors of transmission lines 28 and 31, respectively, and serve to couple these lines to resonant chamber 52.

Detector 54 is connected between housing 55 and rod 56 as shown. An output lead 60 is also connected to rod 56, and passes through an insulating bushing 61 in the bottom of housing 55. The capacitance between the lower end of rod 56 and the bottom of housing 55 provides a by-pass across rectifier or detector 54 for high-frequency currents. Output lead 60 is connected to shunt resistor 33, series capacitor 35, and one of output terminals 34. The other output terminal and housing 55 of resonant chamber 52 are preferably grounded, as shown.

Such a unitary arrangement has the advantage of requiring only a single coupling loop in the tube. It also permits the operation of cavity resonator 15 at a high potential with respect to ground while housing 55 of chamber 52 and the outer conductor of transmission line 28 may be at or near ground potential, it being assumed that a single insulating bushing is provided between the outer conductor of transmission line 31 and housing 55 of chamber 52.

In one successful embodiment of the invention in accordance with Fig. 1, velocity-modulation tube 10 was a Sperry Reflex Klystron Model 417. The carrier frequency of the signal wave was approximately 3,000 megacycles per second. The sinusoidal quench voltage, developed by oscillator 25, had a frequency of 465 kilocycles per second and a value of approximately 12 volts. Source 19 had a total potential of 250 volts; and cathode 12, control electrode 13 and reflector 16 were operated, respectively, at negative voltages with respect to cavity resonator 15 of 199, 190 and 203.

In any of the above-described embodiments of the present invention, the quench frequency is chosen to permit the oscillations of the tube either to build up fully to the equilibrium value during a single oscillation period, thus providing the logarithmic mode of operation; or to build up to a value less than the equilibrium value during each period before quenching occurs. The latter mode is referred to as the linear mode of operation.

Where the expression "reflex tube" is employed, it will be understood that reference is made to an electron tube in which an electron stream is produced by a cathode, passes in a first direction through one or more control electrodes, is reversed in its travel, and passes in the opposite direction through one or more of the same electrodes.

Since many changes could be made in the above construction and many apparently widely different embodiments of this invention could be made without departure from the scope thereof, it is intended that all matter contained in the above description or shown in the accompanying

75

drawings shall be interpreted as illustrative and not in a limiting sense.

What is claimed is:

1. In a superregenerative wave receiver, the combination of a reflex velocity-modulation tube having a cavity resonator, means for rendering said tube alternately oscillatory and non-oscillatory, means for introducing an input wave into said resonator, and utilization means responsive to the average strength of oscillation of said tube including a rectifier element coupled to said resonator.

2. In a superregenerative wave receiver, the combination of a reflex velocity-modulation tube having a cavity resonator therein, means for varying a control voltage applied to said tube to render it alternately oscillatory and non-oscillatory, means for introducing an input wave into said resonator, and utilization means responsive to the average strength of oscillation of said tube including a rectifier element coupled to said resonator.

3. In a superregenerative receiver, the combination of a velocity-modulation electron tube of the reflex type having a cavity resonator therein, means for rendering said tube alternately oscillatory and non-oscillatory, means for introducing an input wave into said resonator, and utilization means comprising a detector coupled to said cavity resonator and responsive to the average strength of oscillation of said tube.

4. Superregenerative receiver apparatus comprising: an oscillator including a cathode electrode, a reflector electrode and a cavity resonator aligned therebetween; means coupled to one of said electrodes for periodically quenching oscillations of said oscillator; means for exciting said resonator in response to a received wave; a detector coupled to said resonator; and a utilization circuit coupled to said detector.

5. In a superregenerative wave receiver, the combination of a reflex velocity-modulation tube having a cavity resonator therein, means for rendering said tube alternately oscillatory and non-oscillatory, coupling means connected to said resonator for introducing an input wave thereto, and a detector in said coupling means for detecting the average strength of oscillation in said resonator.

6. The combination as defined in claim 5 in which said coupling means is resonant at the frequency of the cavity resonator.

7. In a superregenerative wave receiver, the combination of a klystron velocity-modulation tube having a first cavity resonator therein, means for rendering said tube alternately oscillatory and non-oscillatory, a second cavity resonator coupled to said first cavity resonator, means for introducing an input wave into said second cavity resonator, and a detector coupled to said second cavity resonator.

8. In a superregenerative wave receiver, the combination of a velocity-modulation tube having at least one cavity resonator, means for rendering said tube alternately oscillatory and non-oscillatory, means for introducing an input wave into said resonator, and a detector element coupled to said resonator and directly responsive to variations in the strength of the wave therein.

9. In a superregenerative wave receiver, the combination of a reflex tube having a control electrode and a cavity resonator, said cavity resonator being adapted upon excitation to provide an alternating electric field extending in alignment with said control electrode; means includ-

ing a source of varying voltage coupled to said control electrode for rendering said tube alternately oscillatory and non-oscillatory, means for introducing an input wave into said tube, and utilization means comprising a detector coupled to said cavity resonator and responsive to the average strength of oscillation of said tube.

10. The combination as defined in claim 9, in which the reflex tube is of the velocity-modulation type.

11. In a superregenerative wave receiver, the combination of a reflex velocity-modulation tube having therein a cathode, a control electrode and a cavity resonator, said cavity resonator being aligned with said control electrode and said cathode whereby electrons are adapted to flow from said cathode toward said resonator, said control electrode being adapted to regulate the electron flow toward said cavity resonator, and said cavity resonator being oscillatively coercive with electron flow therethrough; means including a source of varying voltage coupled to said control electrode for rendering said tube alternately oscillatory and non-oscillatory; means for introducing an input wave into said resonator; and utilization means comprising a detector coupled to said cavity resonator and responsive to the average strength of oscillation of said tube.

12. In a superregenerative wave receiver, the combination of an electron tube, said tube having therein a cathode, a reflector electrode, and a cavity resonator aligned therebetween and adapted upon excitation to provide an alternating electric field extending in alignment with said electrode and said cathode; means for rendering said tube alternately oscillatory and non-oscillatory; means for introducing an input wave into said resonator; and utilization means responsive to the average strength of oscillation of said tube including a rectifier element coupled to said resonator.

13. The combination as defined in claim 12, in which the electron tube is of the velocity-modulation type.

14. The combination as defined in claim 12, in which the electron tube is of the reflex type.

15. In a superregenerative wave receiver, the combination of a reflex velocity-modulation tube having a cavity resonator therein, said cavity resonator being adapted upon excitation to provide an oscillating electric field; means for varying a control voltage applied to said tube to render it alternately oscillatory and non-oscillatory; means for introducing an input wave into said tube; and utilization means responsive to the average strength of oscillation of said tube including a rectifier element coupled to said resonator.

16. Superregenerative receiver apparatus comprising: an oscillator including a cathode, a control electrode adjacent said cathode, a reflector electrode in alignment with said cathode and control electrode, and a cavity resonator between said reflector electrode and said control electrode and adapted upon excitation to provide an alternating electric field extending in alignment with said electrodes; a source of quench frequency oscillations; means coupling said source to one of said electrodes to periodically quench oscillations in said resonator; means for exciting said resonator by a wave to be received; a detector coupled to said resonator for producing a detected signal corresponding to the average strength of oscillations in said resonator; and a utilization circuit coupled to said detector.

17. Superregenerative receiver apparatus comprising: means for producing a stream of electrons; cavity resonator means for velocity-modulating said electrons; reflecting means for returning said velocity-modulated beam for further interaction with said resonator means, whereby oscillations are produced in said resonator means; means for periodically quenching said oscillations at a quench frequency; means for exciting said resonator means by a received wave; and a detector coupled to said resonator means for producing a signal corresponding to the average strength of oscillations in said resonator, said signal thereby being the modulation envelope of said received wave.
